UNITED STATES PATENT OFFICE

JACOB WACHSMAN, OF BROOKLYN, NEW YORK

ELECTRIC STOP MECHANISM AND CONTACT RING FOR CIRCULAR-KNITTING MACHINES

Application filed December 5, 1929. Serial No. 411,877.

My present invention relates to knitting machines of the circular type in which a vertical shaft is rotatably mounted and carries the spools of thread, first and second circuit closers being provided at different elevations through which the thread passes before passing to a slack take-up device in its travel to the bed of the machine where it is used.

Primarily my present invention has for its object to provide certain improvements in the current conducting brush or finger to which the insulated terminals of the circuit closers are connected and in the collecting ring with which that brush cooperates.

Further, the invention seeks to provide a structure in which the collecting ring is stationary and the brush or contacting finger rotates with the vertical shaft or post of the machine, the finger having a wiping contact with the edge of the ring in order to keep the contacting surface bright and clear.

Further, the invention has for its object to provide slack take-up devices cooperating with the ring as a circuit closer whereby when too much slack in the thread occurs, or the thread breaks, the circuit to the stop magnet will be closed by contact of the take-up device with the bright edge of the contact ring.

Again it is an object to provide for the maintenance of a clear wiping contact surface edge of the ring so that not only will the brush or finger make good contact with the ring but the resilient wire take-up arms, when released into contact with the ring, will have a clean fresh surface to engage.

Further, it is an object to provide a construction in which the ring is stationary and the take-up device turns with the center post of the machine so that when it springs up into engagement with the contact ring it will have a wiping contact therewith and thus assist in keeping the edge of the ring free from lint, corrosion or dirt which would tend to increase the resistance of the electric circuit or render contact poor.

Other objects will in part be obvious and in part be pointed out hereinafter.

To the attainment of the aforesaid objects and ends, my invention consists in the novel

features of construction and in the combination, connection and arrangement of parts, hereinafter more fully described, and then pointed out in the appended claims.

In the drawing:

Figure 1 is a diagrammatic view of a portion of a circular knitting machine with my invention applied.

Figure 2 is a perspective view of the disk-like element which is secured to the shaft and carries the contact fingers or arms and the slack take-up devices.

In the drawing in which like numerals of reference indicate like parts in all of the figures, 1 represents the rotatable central shaft 65 or post of the knitting machine which is mounted in suitable bearings 9 supported from the bed 8. The post 1 is rotated in any suitable manner (not shown) and carries a series of radial arms 2 which support the 70 spindles for the spools 3. Above the arms 2 is another set of radial arms 4 which carry the first circuit closer, (also known as the end detector) the construction of which circuit closer is preferably that disclosed in my 75 co-pending application filed January 15, 1929, Serial No. 332,644 and per se is not of the present invention.

Near the top of the post is mounted a series of arms 6 which support the top box or knot 80 detector circuit closer 7 which may be of the construction disclosed in the aforesaid application or that disclosed in my application filed on even date herewith, Serial No. 411,876.

Beneath the set of arms 2 and secured to the post 1 is a disk 11 from which, preferably at diametrically opposite points, radiate contact fingers or brushes 16 which are insulated from the ring 11 as at 15 and to which the insulated circuit terminals of the circuit closers 5 and 7 are electrically connected as indicated by wires 24 in Figure 1. Mounted on fixed supports 20 through insulating connections 19 and lugs 18 is a contact ring 17 with the under edge of which the brushes or fingers 16 (preferably two or more) have a wiping contact. The ring 17 being stationary the brushes 16 being rotatable rub along the under edge of the ring and assist in maintaining 95 100

its surface bright and clean for good electrical contact.

5 Mounted on the disk 11 are slack take-up devices consisting of brackets 10 having radiating arms, in the outer ends of which are porcelain eyes 12 through which the thread passes. Secured to the brackets 10 are spring wire slack take-up arms 13 having porcelain eyes 14 through which the thread passes and 10 which are projected under the ring 17 so that when released their springy action will throw them up into contact with the lower edge of the ring 17 along which they wipe due to the rotation of the post 1, and effect electrical 15 connection between the ring and the post, the post being grounded to the frame of the machine as is one terminal of the battery 23, the other terminal of which connects to the release magnet 21 that operates the stop lever 22, the magnet 21 being electrically connected by wire 25 with the ring 17.

In operation the thread is passed from the spool 3 through the circuit closer mechanism 5, thence upwardly through the circuit closer mechanism 7, thence downwardly through the eyes 12 and 14 and to the place where the thread is being used (not shown). The slight tension on the thread is sufficient to hold the arm 13 out of contact with the 30 ring 17. Should, however, too much slack occur or should the thread break, the arm 13 will contact the ring 17 and close the circuit. Should the end of the thread from the spool 3 pass the circuit closer 5 that circuit 35 closer will be operated to close the circuit of the magnet 21 at that place and stop the machine. So also if it breaks between the circuit closers 5 and 7, as soon as the end of the thread passes the circuit closer 7 that circuit closer 40 will operate to stop the machine. The circuit closer 7 also has provision for closing the circuit of the release magnet 21 in the event that a knot is formed in the thread before it reaches the circuit closer 7.

45 From the foregoing it will be seen that I have provided a simple and effective mechanism for its intended purpose so constructed that all danger of failure to operate properly is eliminated. The wiping contact between 50 the brushes or fingers 16 and the ring 17 keep the contacting edge of the ring which cooperates with the arm 13 bright and clear and free from accumulation of débris so that when an arm 13 is released it will instantly make good 55 electrical contact with the ring and effect instant stoppage of the machine.

Furthermore should any lint collect on the arm 13 between it and the ring 17 the minute the arm contacts the ring, due to the rotation 60 of the arm with wiping contact of the ring, the friction will clear off the lint and enable electrical contact to occur.

From the foregoing description, taken in connection with the accompanying drawing, it is thought the construction, operation and

advantages of my invention will be clear to those skilled in the art to which it relates.

Wires 26 having their free ends stripped of insulation may be mounted adjacent each post 20 so that if the attendant desires to 70 stop the machine he can do so by touching the end of the wire 26 to the post 20.

What I claim is:

1. In apparatus of the character described wherein is provided a circular knitting machine having electrical stop devices including a stop magnet, and first and second circuit closers, means to connect said circuit closers in circuit with said magnet, said means including a stationarily held conductor ring, 75 supports therefor insulating said ring, an electrical connection between said ring and said stop magnet, said machine including a vertically rotatable post, a disk secured to said post, a contact finger carried by and insulated from said disk and underlying said ring and engaging the edge thereof with wiping contact, and an electrical connection from insulated terminals of said circuit closers to said contact finger for the purposes described. 80

2. In apparatus of the character described wherein is provided a circular knitting machine having electrical stop devices including a stop magnet and first and second circuit closers, means to connect said circuit closers in circuit with said magnet, said means including a stationarily held conductor ring, 85 supports therefor insulating said ring, an electrical connection between said ring and said stop magnet, said machine including a vertically rotatable post, a disk secured to said post, a contact finger carried by and insulated from said disk and underlying said ring and engaging the edge thereof with wiping contact, and an electrical connection from insulated terminals of said circuit closers to said contact finger, said circuit closers having their other terminals grounded to the frame of the machine and said magnet having a terminal grounded to the frame of the machine, a battery being included in the circuit of said magnet substantially as described. 90

3. In circular knitting machines, a rotatable post, a spool carrier mounted thereon, thread guides carried by the post through 105 which the thread passes from a spool on the spool carrier, thread guides including circuit closers controlled by the thread, a contact finger electrically connected with said circuit closers and carried by, rotatable with, 110 and insulated from said post, a fixed contact ring insulated from and mounted on the bed of the machine with which ring said finger has wiping contact, a stop motion magnet, a battery connected in circuit between said circuit closers and said magnet and said ring. 115

4. In circular knitting machines, a rotatable post, a spool carrier mounted thereon, thread guides carried by the post through 120 which the thread passes from a spool on the 125

spool carrier, thread guides including circuit closers controlled by the thread, a contact finger electrically connected with said circuit closers and carried by, rotatable with, and insulated from said post, a fixed contact ring insulated from and mounted on the bed of the machine with which ring said finger has wiping contact, a stop motion magnet, a battery connected in circuit between said circuit closers and said magnet and said ring, a thread guide bracket mounted on, turning with and electrically connected to said post and having a thread-passing eye, a spring take-up arm mounted on and in electrical contact with said bracket and having a thread-passing eye, said take-up arm projecting beneath said ring and adapted when released to spring up into wiping contact with said ring to close a circuit through said stop magnet for the purposes described.

JACOB WACHSMAN.
